PUMPING APPARATUS

John T. Hayward, Tulsa, Okla.

Application June 26, 1942, Serial No. 448,603

6 Claims. (Cl. 103—204)

This invention relates to pumps and particularly to pumping mechanism for handling fluids carrying solids in suspension.

When pumping fluids carrying solids or semi-solids in suspension, such as clay or mud slurries commonly employed in drilling oil and gas wells by the rotary method, it is often desirable to pump a small portion of the mud to mud analysis or testing devices. Normally, small pumps are employed and the valves and ports of such pumps become clogged very quickly by the particles of the drill cuttings, cotton seed hulls, celotex and other addition materials commonly added to drilling muds. When screens or strainers are placed over the ends of the pump suction pipes, such screens, if fine enough to exclude the undesirable materials, quickly become clogged by such materials and render the pump inoperative.

The principal object of this invention is to provide an improved form of pumping mechanism whereby the suction screens are substantially kept clear of the undesired materials and clogging hindered, while the pump continues to deliver the desired stream of mud fluid relatively uninterruptedly.

In accordance with a general embodiment of this invention, suitable means is provided in operative association with the pump suction mechanism, which has screened inlets, whereby reversal of the fluid flow back through the suction pipe and screen may be effected either continuously or intermittently as may be desired, in various ways, several of which are described hereinafter by way of example.

Other objects and advantages of this invention will become apparent from the following detailed description, when read in conjunction with the accompanying drawing which illustrates several useful embodiments in accordance with this invention.

In the drawing:

Fig. 1 illustrates an arrangement of apparatus constituting one embodiment in accordance with an embodiment of this invention;

Fig. 2 is a sectional elevation of a pumping mechanism in accordance with another embodiment of this invention; and

Fig. 3 illustrates still another embodiment in accordance with this invention.

Referring to the drawing and to Fig. 1 in particular, the numeral 1 designates a container for fluid to be handled by the pump. Container 1 may be a tank, ditch or pit in which the fluid is stored or through which the fluid may be flowing. The inlet end of a suction pipe 2 is im-

mersed in the body of the fluid in container 1 and is covered by a screen 3 having a mesh fineness adapted to exclude solid or semi-solid particles of undesired size from the suction pipe.

5 The opposite end of suction pipe 2 is connected to a pump cylinder 4 having a discharge pipe 5. Pump cylinder 4 may be of any suitable or conventional design and may be a reciprocating, rotary or centrifugal pump, which is driven by means of a shaft 6 connected to any suitable power source (not shown). A branch conduit 7 is connected into suction pipe 2 at any suitable point intermediate the ends of the suction pipe. Reciprocably mounted in branch conduit 15 7 is a plunger 8 which is movable through a packing gland 9 arranged in the outer end of branch conduit 7 to form a fluid tight seal between the plunger and the branch conduit. A crank arm 10 has one end pivotally connected at 20 11 to the outer end of plunger 8 and its other end pivoted at 12 to an eccentric crank 13 which is rotated by a shaft 14, which may be driven by any suitable power source (not shown). Rotation of crank 13 reciprocates plunger 8 in branch conduit 7, the stroke being limited by the throw of crank 13.

The above described mechanism is operated in the following manner: Pumping is begun in the usual manner with pump cylinder 4 drawing fluid 30 from container 1 through screen 3 and suction pipe 2 and discharging the fluid through discharge pipe 5 to the desired place of delivery (not shown). Simultaneously with the beginning of the pumping operation, or as soon thereafter as 35 screen 3 shows signs of becoming clogged, plunger 8 is set in operation. The reciprocating movement of plunger 8 in branch conduit 7 produces a reverse pulsation in the stream of fluid traveling through the suction pipe and on each inward 40 stroke of the plunger some of the fluid is forced back through the suction pipe and screen under sufficient pressure to blow from the screen any clogging material which may have collected thereon. As indicated previously, crank 13 operating 45 plunger 8 may be driven by any suitable power source independent of pump 5, or it may be driv- 50 ingly connected in any convenient and suitable manner to shaft 6, as indicated by the broken line 15. 55 Plunger 8, branch conduit 7 and crank 13 constitute a pulsating means and the diameter of plunger 8 and its rate of displacement must be such that when its rate of displacement is a maximum, it will exceed the rate of delivery of pump 4. Under these conditions the reciproca-

tion of plunger 8 will produce reverse flow of fluid in pipe 2 and through screen 3 without affecting the delivery of pump 4. It will be understood that plunger 8 may be kept in continuous operation or may be run intermittently as the condition of screen 3 may indicate.

Fig. 2 illustrates another embodiment in accordance with this invention in which the suction valve arrangement of a pump is adapted to automatically produce reverse flow of fluid for purposes of keeping the suction pipe and screen clear. In this embodiment, a pump body 16 of generally tubular form and horizontally disposed, is provided at one end with a suction valve chamber 17 and at the other end with a discharge valve chamber 18. Suction valve chamber 17 is provided with an inlet connection 19 which is connected to a suction pipe, such as suction pipe 2 of the previously described embodiment. Inlet connection 19 communicates with the interior of chamber 17 through an upwardly opening circular port 20 provided with an annular seat 21 upon which a conical valve 22 is seated and adapted to open and close the port 20 by vertical movement relative thereto. The top of suction valve chamber 17 is closed by a cover plate 23 arranged directly above valve 22 and provided with a downwardly extending boss 24 forming a stop to limit the upward travel of valve 22 relative to seat 21. Discharge valve chamber 18 is provided with a discharge connection 18a and communicates with the interior of pump body 16 through a circular port 25 provided with an annular seat 26 and a valve 27. A cover plate 28 is arranged above valve 27 and is also provided with a downward extension 29 to limit the upward travel of valve 27. The degree of clearance between valve 22 and boss 24 is designed to be substantially greater than its normal degree of clearance in relation to that between valve 27 and extension 29.

Connected to an intermediate portion of pump body 16 and extending at right angles thereto is a cylinder 30 having a plunger 31 slidably disposed therein. The outer end of cylinder 30 is closed by a packing gland 32 which forms a fluid tight seal about the body of plunger 31. The outer end of piston 31 is provided with a piston rod 33 for connection to any suitable power mechanism (not shown) adapted to reciprocate piston 31 in cylinder 30.

In operation, reciprocation of plunger 31 produces corresponding action of valves 22 and 27. That is, on the out-stroke of the plunger, suction is created within body 16 raising valve 22 and admitting fluid to the interior of the cylinder 30 from suction pipe 2, and on the in-stroke, the resulting compression forces the fluid to lift valve 27 for discharge through outlet 18a. By providing a greater than normal degree of clearance between suction valve 22 and its stop 24, the closing of suction port 21 will be delayed, with the result that the compression stroke of piston 31 will force some of the fluid in the pump body back through the suction port and thence through suction pipe 2 and screen 3 and thereby dislodge any material which has adhered to the screen.

The degree of clearance above valve 22 will preferably be so designed that the resulting seating lag will only be sufficient to permit a portion of the fluid to flow in reverse, the remainder being discharged through discharge port 25 and outlet connection 18a to thereby provide a continuous discharge of fluid from the cylinder 30

to the desired point of delivery. It will be understood that other forms of valves than that shown may be employed, such as conventional ball valves or the like. Also various types of reciprocating pumps may be adapted to operate in accordance with this embodiment.

The embodiment of Fig. 3 illustrates another embodiment of the arrangement illustrated in Fig. 2 and described above. In accordance with the embodiment of Fig. 3, an armature 34 of an electromagnet 35 is threadedly inserted through the cover plate 23 and extends into suction valve chamber 17, where the inner end of armature 34 forms a stop for valve 22 at the normal distance therefrom. Normally, therefore, suction valve 22 will operate at normal timing without lag and no back-flow will occur. The electromagnet is connected by conductor leads 36 and 37 to a battery 38 or other suitable source of current. A switch 39 is provided in the circuit of the electromagnet. In this embodiment, cover plate 23 will be constructed of brass or other nonmagnetizable material, while valve 22 will be constructed of suitable magnetizable material such as iron or steel.

With this embodiment, when it is desired to clear the suction pipe and screen, switch 39 is closed thereby energizing armature 34 with the result that, when valve 22 is raised from its seat during the suction stroke of the pump and comes up against the end of armature 34, it will be held against the armature by magnetic attraction and will remain off of seat 21 as long as current flows through the winding of the electro-magnet. With suction valve 22 held from its seat, the discharge stroke of the pump will cause reverse flow of fluid through the suction passageways, producing the previously described screen-clearing action. The electromagnet may be energized intermittently or at suitable regular intervals, or whenever the screen begins to become clogged.

It will be understood that various changes and modifications may be made in the details of the apparatus herein described within the scope of the appended claims but without departing from the spirit of this invention.

What I claim and desire to secure by Letters Patent is:

1. In pumping apparatus wherein a pump suction is provided with a suction valve and with a screen for straining extraneous matter from the fluid being pumped, the improvement for hindering clogging of the screen comprising, means associated with the suction valve of the pump to delay the normal operating period thereof whereby to produce reverse flow of said fluid through said screen.

2. In pumping apparatus wherein a pump suction is provided with a screen for straining extraneous matter from the fluid being pumped, the improvement for hindering clogging of the screen comprising, means associated with the suction of the pump and operative during the normal operation of the pump to cause a portion of the fluid entering the pump suction to reverse its direction therein and discharge through said screen.

3. In pumping apparatus wherein a pump suction is provided with a screen for straining extraneous matter from the fluid being pumped, the improvement for hindering clogging of the screen comprising, plunger means associated with the pump suction and operative therein to force a portion of the fluid entering the pump suction to reverse its direction and discharge through said screen.

4. Pumping apparatus comprising, in combination with a pump having suction and discharge valves and a suction pipe having a screen associated therewith, means associated with said suction valve for extending the normal off-seat period thereof to thereby cause a portion of the fluid passing the suction valve to reverse its direction and discharge through said screen during the discharge stroke of the pump.

5. Pumping apparatus comprising, in combination with a pump provided with a suction pipe having a screen associated therewith, an auxiliary cylinder communicating with said suction pipe between said pump and said screen, and a plunger reciprocable in said cylinder to cause a portion

of the fluid being drawn through said suction pipe and said screen to reverse its direction of flow and discharge through said screen.

6. In a pump having normally operating mechanism and whose suction is provided with a suction valve and with a screen for straining extraneous matter from the fluid being pumped, the improvement for hindering clogging of the screen comprising, means in addition to but associated with the operating mechanism of the pump, said means being operative during the normal continued pumping operation of the pump to effect reverse flow of said fluid through said screen.
